UNITED STATES PATENT OFFICE.

LOUIS G. LAUREAU, OF NEW YORK, N. Y.

APPARATUS FOR STRIPPING INGOTS CAST IN MOLDS.

SPECIFICATION forming part of Letters Patent No. 254,341, dated February 28, 1882.

Application filed November 29, 1881. (No model.)

To all whom it may concern:

Be it known that I, LOUIS G. LAUREAU, a citizen of the United States, residing in the city, county, and State of New York, have invented a new and useful Method and Apparatus for Stripping Ingots Cast in Molds, and the following is a specification of the same.

My improvement consists in a combination of mechanical contrivances by means of which ingots of cast metal can be taken out of the molds and charged upon ingot-bogies, or into heating-furnaces, without the use of casting-pits and ingot-cranes heretofore employed in establishments where cast metal—such as Bessemer or open-hearth steel—is manufactured.

In the accompanying drawings, Figure 1 is a plan of the apparatus; Fig. 2, a side elevation of the same, partly in section; and Fig. 3 is an elevation showing the mechanism of an adjustable face-plate, hereinafter described.

A is a car, upon which stand one or more ingot-molds, B B, hinged to the stationary car-platform at C. This car is first brought to the Bessemer converter, or to the furnace where the molds are filled. It is then taken to its proper position, as shown in the plan. The projection D on the car-platform comes just under the lip E of the roller-frame F. This prevents the side tipping of the car when the ingot-molds are pulled over. When the car is in place the ingot-molds are tipped and assume the position shown in Fig. 1, and in full lines in Fig. 2, their upright position being indicated by dotted lines in said figure. The spring G, upon which they fall, prevents jar. For the purpose of illustration I have shown a spiral metallic spring; but a simple block of rubber may be used.

The tipping of the ingot-molds may be accomplished in many ways—by direct action of a steam or hydraulic cylinder, or, as shown in the drawings, by means of hooks H H', attached to chains wound around a drum, J, worked by a belt and pulley or a direct engine.

When the ingot-molds are lying horizontally the lugs K come opposite and against the stops L. The face M of these stops is preferably made movable. Before the ingot-molds are pulled over, the face-plates M of the stops L are drawn down by means of the lever V, rod V', and bell-crank levers W, (shown in Fig. 3,) so

that the lugs K cannot strike the upper corners of the stops, and when they (the molds) are lying on their side the face-plates are drawn up again until they fit tight against the lugs K. The holes C in the ingot-mold hinges are made oval, so as to give the necessary play to insure a close contact of the lugs K against the stops L, and prevent any push against the hinge-pins.

Instead of making the face of the stops movable, the upper corners might be rounded, so as to avoid striking the lugs as the molds come down. The oval hinge-hole would allow the lugs and stops to come close together, but the rounded surface of the stops might cause the lugs to slip up under pressure. For this reason the movable face-plates are preferably employed. The face-plates of the stops being adjusted, the cylinder N, (steam or hydraulic,) which slides on ways O O, is brought by means of the pushing cylinder P in front of the ingot-mold. Power being applied, the ingot is pushed out of the mold by means of the piston-rod Q. It passes over the roller R onto the ingot-bogie S. When all the ingots on the car have been stripped the molds are straightened up to a standing position by means of the hooks and chains above described. The chain X is bifurcated at x into separate chains Y Y', passing over pulleys U U', to which chains the hooks H H' are respectively attached. The chain Y is employed for straightening up the molds and the chain Y' for pulling them over. The positions of the chains when straightening up the molds are indicated in full lines, and their positions when pulling the molds over in dotted lines.

When the ingots are to be placed directly into a heating-furnace the car carrying the hinged ingot-mold filled with metal is brought in front of the furnace-door, the molds are tipped one at a time, and the ingot is punched out directly into the furnace by means of a traveling cylinder or stationary cylinders placed in front of each furnace-door. These cylinders can be used afterward to withdraw the ingots from the furnace.

In order to protect the car-platform, I preferably use the movable stools T, made of fire-brick or cast-iron, easily replaced when worn out by the falling stream of metal.

I do not claim ingot-molds mounted on a movable car, nor the cylinder to force ingots out of molds; but,

Having thus described my invention, what I claim as new therein, and desire to secure by Letters Patent, is—

1. The ingot-mold B, mounted on a car, A, by a hinged joint having an elongated hole, C, and having lugs or projections K, in combination with stops L, and with the punching-cylinder N and piston O, substantially as and for the purposes set forth.

2. The combination of the hinged mold B with lugs K, the stops L, the movable face-

plates M, and cylinder N and piston O, substantially as and for the purposes set forth.

3. The combination of the car A, hinged ingot-mold B, roller-frame F, and lip E, to prevent the tipping of the car, as explained.

4. The combination of the car A, hinged mold B, support G, stops L, hooks H H', chains X Y, and movable cylinder N and piston O, substantially as and for the purposes set forth.

L. G. LAUREAU.
